RAIL GUARD

James H. Asselin, Winnetka, Ill.

Application February 9, 1948, Serial No. 7,090

7 Claims. (Cl. 238—23)

1

This invention relates to a rail guard structure to the running rails of railway track. More particularly it relates to a rail guard assembly having special means for adjusting the rail guard with respect to the running rail so as to provide the proper space therebetween, and to maintain the guard rail in such adjusted position. It is a general object of the invention to provide such an assembly.

A further object of the invention resides in providing a guard rail assembly in which the guard rail is not bolted or otherwise anchored to the running rail, but which nevertheless properly maintains track alignment and prevents wheel flanges from striking frog points by maintaining a standard width flangeway between the two rails. The invention thus prevents high speed trains from lurching when passing over switch turnouts.

It is of course well known that changes in temperature will cause expansion and contraction of rails. Because the guard rail is not bolted or fastened to the running rail, expansion or contraction of the latter will not affect the guard rail and the arrangement thus prevents kinking of the running rail along the guard rail during expansion.

Another more specific object of the invention resides in the provision of a pair of specially designed tapered end blocks at each end of the guard rail assembly, each pair being provided with means to permit relatively adjustment of the blocks making up that pair in such a manner as to control the distance between the guard rail and the running rail, and thus providing a dual adjustment.

Still further the invention provides for special base plates which cooperate with rail braces which engage the guard rail at spaced points and also with the specially designed tapered end blocks referred to so as to maintain the proper spacing between the guard rail and the running rail at all times and also to prevent the guard rail from tilting or from moving vertically or longitudinally.

Moreover, it is an object of the invention to provide a guard rail assembly in which adjustment of the space between the guard rail and the running rail may be effected without having to remove the guard rail from its resting position on the base and tie plates.

Another important object of the invention resides in the provision of such a rail guard assembly which is of simple construction, and which may be installed simply and adjusted

2

easily. The assembly does not require any special clamps nor does it require any change or weakening of the running rail which would be occasioned, for example, by the drilling of holes therethrough as is frequently the case with many known rail guard structures.

These and other objects of the invention will become more apparent from the following description and claims when read in conjunction with the accompanying drawings, in which:

Fig. 1 is a plan view of an assembly showing a preferred embodiment of the invention;

Fig. 2 is an enlarged plan view of the left end portion of the arrangement shown in Fig. 1;

15 Fig. 3 is an enlarged vertical section taken on the lines 3—3 of Fig. 5;

Fig. 4 is an enlarged exploded view of the end block structure, in perspective;

Fig. 5 is a horizontal section taken on the line 20 5—5 of Fig. 3;

Fig. 6 is the side elevation of one of the adjustable end blocks;

Fig. 7 is a side elevation of the stationary wedge block looking toward the wedge surface;

25 Fig. 8 is a sectional view on the line 8—8 of Fig. 7;

Fig. 9 is a side elevation of the movable wedge block looking toward the wedge surface, and

Fig. 10 is a sectional view on the line 10—10 of Fig. 9.

30 The view illustrated in Fig. 1 shows the entire guard rail assembly. In this figure the reference numeral 10 indicates the railroad ties. The running rail 11 is secured to the ties through the medium of the usual tie plates 12 and special base plates 13. The invention contemplates the use of at least two such base plates 13, one at each end of the guard rail assembly. If the guard rail is of substantial length, it is also desirable to employ additional base plates intermediate the end base plates. One of such intermediate base plates is also illustrated in Fig. 1 of the drawings.

45 In accordance with the invention the base plates 13 are of a width sufficient to permit them to be disposed over at least two of the ties 10 and they are secured to the ties by means of spikes which may be driven through the holes 14 in the base plates and into the ties therebelow. The running rail 11 is disposed on the base plates 13 and the tie plates 12 and is secured to the ties 10 by means of spikes 15 which are driven through holes in the base plate and into the ties.

50 55 The base plates 13 and the tie plates 12 also

support the guard rail which in the drawings is indicated by the reference numeral 16.

The guard rail 16 is also fastened to the ties 10 on one side by means of spikes which are driven through holes 14' in the base plates 13, and which, as shown in Fig. 2, have an off-set cut out to provide longitudinal adjustment.

The guard rail is adjustable with respect to the running rail and the means of adjustment comprise an important aspect of the invention as will perhaps already be clear. Disposed on each base plate 13 is an adjustable rail brace 17. These rail braces 17 may preferably be of the type disclosed in my Patents Nos. 2,419,701; 2,426,137; and 2,426,138. They serve the purpose of preventing the guard rail from tilting inwardly and also prevent the guard rail from moving laterally away from its adjusted position. They also serve an additional purpose, as will be referred to hereinafter.

At each end of the assembly the guard rail 16 and the running rail 11 are separated by special tapered end blocks. Referring now to Fig. 2, which is an enlarged view of the left end of the assembly as shown in Fig. 1, one pair of the end blocks is illustrated therein. This pair is comprised of a stationary end block 18 which is disposed adjacent to the running rail 11, and a movable end block 19 which is disposed adjacent to the guard rail 16. The specific construction of these end blocks 18 and 19 is perhaps more clearly shown in Fig. 4, which is an exploded perspective view. It will be noted from that view that the end block 18 has an outer side wall 20 which is adapted to be disposed adjacent the web 21 of the running rail 11 as shown in Fig. 3. This wall 20 of the end block 18 has curved upper and lower surfaces 22 and 23 which are complementary in shape to the curved surfaces at the base of the rail head and at the juncture of the web of the running rail and the base of the running rail, as also will be clearly apparent from Fig. 3.

The end block 18 has an inner side flat wall 24 which is tapered at an angle with respect to the wall 20. This tapered wall 24 is provided with a laterally extending tongue 25. The tongue has a series of vertically disposed holes 26 which pass therethrough. This tongue 25 extends from the wall 24 at one end of the end block 18. At the other end of the end block 18 the tapered wall 24 is provided with a rectangular cut-out 27 which in width is slightly greater than the thickness of the tongue 25.

The end block 18 is also provided with a central transverse opening or hole 28 to receive a bolt 29 and the wall 20 of the end block 18 is recessed with a rectangular cut-out 30 so that the head 31 of the bolt 29 will be countersunk when the device is in assembled position, as is clearly shown in Fig. 3 of the drawings.

The complementary end block 19 which is also shown to good advantage in Fig. 4, is provided with an outer wall 32 adapted to be disposed adjacent the web 33 of the guard rail 16. This wall 32 is curved at its upper and lower edges so as to conform to the curved surfaces of the guard rail 16 beneath the head thereof and at the juncture point between the web and the base of the rail. This will be evident from examination of Fig. 3. The end block 19 also has a tapered wall 34 which is disposed at an angle with respect to the wall 32. The angle of taper of wall 34 is the same as that of the tapered wall 24 of the end block 18 but is tapered in an opposite direction so that the tapered walls 24 and 34 are comple-

mentary. This wall 34 is provided at one end with a laterally extending tongue 35 having a series of holes 36 therein. This tongue is similar in dimension and shape to the tongue 25 of the end block 24. The tongue 35 is also dimensioned so that when the two end blocks 18 and 19 are disposed in adjacent position with the tapered walls 24 and 34, respectively, in engagement with each other, the tongue 35 of the end block 19 will be disposed within the cut-out or recess 27 of the end block 18. Similarly, the end block 19 at its other end has a cut-out or recess 37 which is adapted to receive the tongue 25 of the end block 18 when the two end blocks 18 and 19 are in assembled position.

The end block 13 is provided with an elongated opening 38 which passes transversely through the end block. The width of this opening is just sufficient to permit the shank of the bolt 29 to pass therethrough.

Preferably, the end blocks are constructed of steel, as are the rail braces 17, and the tie and base plates 10 and 13.

It should now be apparent that when the end blocks 18 and 19 are disposed in the position shown in Figures 1, 2 and 3, in particular, with the hole in the stationary block 18 in alignment with the bolt hole 39 in the web of the guard rail, that the bolt 29 may be passed through each of the blocks 18 and 19 and then through the hole 39 in the web 33 of the guard rail 16 and then through a filler member 40 (Fig. 3). The assembly is completed by a washer 41 and by the nut 42. Before tightening the nut 42 the end block 19, because of the elongated hole 38 therein, may be moved longitudinally with respect to the stationary end block 18. Such longitudinal movement of the end block 19 makes it possible to adjust the space between the running rail 11 and the guard rail 16. When the proper adjustment of this space has been effected, the nut 42 is tightened and the assembly is then ready for use.

With reference to Fig. 1, there is a similar arrangement at the right end of the assembly and this is also comprised of two end blocks 18 and 19 similar to the end blocks which have been described in detail.

After the end blocks at each end of the assembly have been adjusted and tightened in the manner which has been mentioned, each pair of end blocks may be additionally locked in adjusted position by passing a steel cotter pin or the like through the appropriate hole of the series of holes 26 and 36 in the tongues 35 and 25, respectively, of the end blocks.

To prevent the guard rail 16 from moving longitudinally with respect to the running rail 11, it is desirable to provide small steel stop blocks 43, as shown in Fig. 1. These stop blocks 43, which extend upwardly above the base of the guard rail may be welded to the upper surfaces of the two end base plates 13, as shown.

While the rail braces 17 may take various forms, they are preferably, as indicated of the forms illustrated in my prior patents Nos. 2,419,701; 2,426,137; and 2,426,138. While reference may be had to those patents for a more detailed description, it should perhaps be mentioned here that they include, broadly speaking, a rectangular block 44, which may be in this case welded to the upper surface of the base plate 13, the block 44, on its surface which faces the guard rail, being provided with a longitudinal groove which is adapted to receive a tongue 45

which extends laterally from the outer surface of a wedge member 46, and a brace member 47. The surface of the wedge member 46 facing the guard rail is tapered with respect to the outer surface of the wedge member and is also, in vertical section, semi-circular in shape. The brace member 47 has a surface engaging the guard rail 16 under the head thereof and on the upper surface of the base. It also has a surface which is complementary in shape to the tapered semi-circular surface of the wedge member 46. The brace member 47 may be additionally secured to the base plate 13 by means of a bolt 48 which passes vertically upwards through the base member and then through the brace member itself and which bolt is capped with a suitable nut as shown.

It should now be apparent that such a rail brace 17 can be employed effectively to adjust the guard rail in the direction of the running rail 11 and that it also will be effective to prevent the guard rail from tilting outwardly or rising vertically.

In the arrangement which has been described, and referring again now to Fig. 1, it will be seen that the guard rail 16 may be adjusted with respect to the running rail 11 by a plurality of adjustable elements, these adjustable elements being the pairs of end blocks 18 and 19 at each end of the assembly, and the three rail brace members 17 which are, as described, secured with respect to the three base plates 13 illustrated in this figure.

It is an important feature of the invention that the whole assembly can be placed into effective operation without in any way damaging the running rail or without the necessity of altering or placing holes in any part of the running rail 11. Moreover, in accordance with the invention it should now be clear that the guard rail is not bolted or otherwise anchored to the running rail 11 in any manner, and yet, in accordance with the arrangement illustrated track alignment is effectively maintained and the wheel flanges of railroad cars are prevented from striking frog points. The assembly thus maintains the standard width flangeway between the two rails, and it also thus prevents high speed trains from lurching when passing over switch turnouts.

The rail braces 17, as already mentioned, prevent the guard rail 16 from tilting outward or from rising upwardly. The tapered end blocks 18 and 19 being fastened to the guard rail, are adjustable with the adjustable rail braces to provide any desired flangeway width. The end blocks with their tongue and groove arrangements, also prevent vertical movement of the guard rail and assist the rail braces 17 in keeping the guard rail from dangerous movement.

It should now be apparent that modifications of the invention as described, can be effected without departing from the scope of the invention. For example, instead of having the elongated slot 38 in the end block 19, as illustrated in Fig. 4 of the drawings, this elongated slot 38 can be provided in the end block 18, while the end block 19, in this event, is provided only with a hole for the passage of the bolt 29. With such an arrangement, the block 19 will remain stationary while the adjustment of the space between the guard rail 16 and the running rail 11 will be effected by moving the block 18 longitudinally with respect to the block 19.

Other changes in the shape and arrangement

of the parts may also be made without departing from the invention which is not, therefore, to be limited by this disclosure except as indicated in the following claims.

5 I claim:

1. A guard rail assembly comprising, a running rail and a guard rail parallel to and spaced from the running rail, a plurality of supporting plates extending transversely and immediately beneath both of said rails, a pair of adjustable spacer blocks disposed between the running rail and the guard rail adjacent one end of the guard rail, a similar pair of spacer blocks adjacent the other end of the guard rail, each of the spacer block pairs having facing surfaces lying in a plane at an angle to the rails to provide for relative adjustment of the blocks of each pair to vary the spacing between the running rail and the guard rail, means for bolting the blocks of each pair to only the guard rail in any of their respective adjusted positions, and a plurality of adjustable rail braces mounted on said supporting plates engaging the guard rail on the side farthest from the running rail and means for adjusting said rail braces to conform to spacing movement of said guard rail.

2. A guard rail assembly comprising, a running rail and a guard rail parallel to and spaced from the running rail, a plurality of supporting plates extending transversely and immediately beneath both of said rails, the supporting plates at each end of the guard rail being of a width sufficient to span two spaced railroad ties, a pair of adjustable spacer blocks disposed between the running rail and the guard rail adjacent one end of the guard rail, a similar pair of spacer blocks adjacent the other end of the guard rail, each of the spacer block pairs having facing surfaces lying substantially in a plane at an angle to the rails to provide for relative adjustment of the blocks of each pair to vary the spacing between the running rail and the guard rail, means for bolting the blocks of each pair to only the guard rail in any of their respective adjusted positions, a plurality of adjustable rail braces mounted on said supporting plates and engaging the guard rail on the side farthest from the running rail and means for adjusting said rail braces to conform to spacing movement of said guard rail.

3. A guard rail assembly comprising, a running rail and a guard rail parallel to and spaced from the running rail, a plurality of supporting plates extending transversely and immediately beneath both of said rails, the supporting plates at each end of the guard rail being of a width sufficient to span two spaced railroad ties, a pair of adjustable spacer blocks disposed between the running rail and the guard rail adjacent one end of the guard rail, a similar pair of spacer blocks adjacent the other end of the guard rail, each of the spacer block pairs having facing surfaces lying in a plane at an angle to the rails to provide for relative adjustment of the blocks of each pair to vary the spacing between the running rail and the guard rail, means for bolting the blocks of each pair to only the guard rail in any of their respective adjusted positions, and a plurality of adjustable rail braces mounted on said supporting plates and engaging the guard rail on the side farthest from the running rail, there being one of said adjustable rail braces mounted on each of the supporting plates which are at the ends of the guard rail, means for adjusting said rail brace to conform to spacing movement of said guard rail, and stop blocks integral with

said end supporting plates and positioned to about the opposite ends of said guard rail to prevent longitudinal movement thereof.

4. A guard rail assembly comprising, a running rail and a guard rail parallel to and spaced from the running rail, a plurality of supporting plates extending transversely and immediately beneath both of said rails, a pair of adjustable spacer blocks disposed between the running rail and the guard rail adjacent one end of the guard rail, a similar pair of spacer blocks adjacent the other end of the guard rail, each of the spacer block pairs having facing surfaces lying in a plane at an angle to the rails to provide for relative adjustment of the blocks of each pair to vary the spacing between the running rail and the guard rail, the facing surfaces of each of said blocks each having a laterally extending tongue of substantially rectangular section at one end thereof and an elongated groove of substantially rectangular section at the other end, the tongue of each of the blocks of a pair engaging the groove of the other block of the pair and extending beyond the end of the mating block, means cooperating with said tongue and said mating block for selectively blocking relative movement of said blocks in at least one direction, means for bolting the blocks of each pair only to the guard rail in any of their respective adjusted positions, a plurality of adjustable rail braces mounted on said supporting plates and engaging the guard rail on the side farthest from the running rail and means for adjusting said rail braces to conform to spacing movements of said guard rail.

5. In a rail guard assembly, a metal supporting plate disposed immediately beneath the running rail and the guard rail, said supporting plate having a width sufficient to span two spaced railroad ties, a pair of adjustable spacer blocks disposed between the guard rail and the running rail, the spacer blocks having facing surfaces lying in a plane at an angle to the rails to provide for relative adjustment of the blocks to vary the spacing between the running rail and the guard rail, means for bolting said blocks to the guard rail only in any one of their adjusted positions, the facing surfaces of said blocks each having a laterally extending tongue of substantially rectangular section at one end thereof and an elongated groove of substantially rectangular section at the other end, the tongue of each block engaging the groove of the other block and extending beyond the end of the mating block, means cooperating with said tongue and said mating block for selectively blocking relative movement of said blocks in at least one direction, means for bolting both blocks to only the guard rail in any one of their adjusted positions, an adjustable rail brace mounted on said supporting plate and engaging the guard rail on the side farthest from the running rail and means for adjusting said rail brace to conform to the spacing movement of said guard rail.

6. In a rail guard assembly, a metal supporting plate disposed immediately beneath the running rail and the guard rail, said supporting plate having a width sufficient to span two spaced railroad ties, a pair of adjustable spacer blocks dis-

posed between the guard rail and the running rail, the spacer blocks having facing surfaces lying in a plane at an angle to the rails to provide for relative adjustment of the blocks to vary the spacing between the running rail and the guard rail, means for bolting said blocks to the guard rail only in any one of their adjusted positions, the facing surfaces of said blocks each having a laterally extending tongue of substantially rectangular section at one end thereof and an elongated groove of substantially rectangular section at the other end, the tongue of each block being adapted to be engaged in the groove of the other block, means for bolting both blocks to only the guard rail in any one of their adjusted positions, and an adjustable rail brace mounted on said supporting plate and engaging the guard rail on the side farthest from the running rail, said adjustable rail brace comprising a brace member for engaging the guard rail, a stationary block member, and a wedge member disposed between said brace member and said block member.

7. In a rail guard assembly, a metal supporting plate disposed immediately beneath the running rail and the guard rail, said supporting plate having a width sufficient to span two spaced railroad ties, a pair of adjustable spacer blocks disposed between the guard rail and the running rail, the spacer blocks having facing surfaces lying in a plane at an angle to the rails to provide for relative adjustment of the blocks to vary the spacing between the running rail and the guard rail, the facing surfaces of said blocks each having a laterally extending tongue of substantially rectangular section at one end thereof and an elongated groove of substantially rectangular section at the other end, the tongue of each block being adapted to be engaged in the groove of the other block, means for bolting both blocks to only the guard rail in any one of their adjusted positions, and an adjustable rail brace mounted on said supporting plate and engaging the guard rail on the side farthest from the running rail, said adjustable rail brace comprising a brace member for engaging the guard rail, a stationary block member, and a wedge member disposed between said brace member and said block member, the contacting surfaces of said block member and said wedge member having complementary tongues and grooves, and the contacting surfaces of said wedge member and said brace member being semi-cylindrical in vertical transverse section.

JAMES H. ASSELIN.
